RIBBED WHEEL CENTER

Richard H. Clement, 10900 Jann Court,
La Grange, Ill. 60525

Filed Jan. 12, 1972, Ser. No. 217,430

Term of patent 14 years

Int. Cl. D12—16

U.S. Cl. D14—30

FIG. 1

FIG. 2

FIG. 3

FIG. 1 is a top plan view of a ribbed wheel center showing my new design;

FIG. 2 is a side elevational view of the ribbed wheel center of FIG. 1; and,

FIG. 3 is a fragmentary sectional view of the ribbed wheel center of FIG. 1, taken along line 3—3 thereof.

I claim:

The ornamental design for a ribbed wheel center, as shown.
